UNITED STATES PATENT OFFICE.

FRIEDRICH DICKENSCHIED, OF BERLIN, GERMANY, ASSIGNOR TO GENERAL ELECTRIC COMPANY, A CORPORATION OF NEW YORK.

ELECTRIC INCANDESCENT LAMP.

1,118,402.

Specification of Letters Patent. Patented Nov. 24, 1914.

Application filed July 15, 1912. Serial No. 709,492.

To all whom it may concern:

Be it known that I, FRIEDRICH DICKENSCHIED, subject of the German Emperor, and residing at Berlin, Germany, have invented certain new and useful Improvements in Electric Incandescent Lamps, of which the following is a specification.

In the manufacture of metal filament lamps it has usually, up to the present, been the rule to arrange the long filament in the lamp in such a manner that the lighting surface was approximately distributed over a circular cylinder. The disadvantage of this arrangement is that the distribution of light from the lamp in different directions is unequal and only approximately uniform perpendicularly to the axis. The different suggestions made up to the present to do away with this drawback have not attained practical importance as the requirements with which such supports must comply in manufacturing lamps on a large scale has not been taken sufficiently into consideration.

One of the objects of the present invention is to secure as far as possible a uniform distribution of light in all directions by using a support of simple construction and arranged in such a manner that the filament can be readily attached to the support.

The nature of my invention and further advantages will best be understood by reference to the accompanying drawing showing one embodiment thereof in which—

Figure 1 is a view in perspective of the support with a filament wound thereon; Fig. 2 is a plan view; and Fig. 3 is a view in perspective taken at a right angle to Fig. 1.

Three groups of supports or holding devices are provided for the filament; the group $a, a^1, a^2 \dots$ at the apex of the central stem S are arranged in the form of radii of a semi-circle and are all located in a plane passing through the axis; the second group $b, b^1, b^2 \dots$, the outer members b, b^1 of which serve as connections to the leads d, d^1 , are secured at the base of the stem in the same plane as the first group and are also arranged in the form of radii of a semi-circle; the third group $c, c^1, c^2 \dots$ are secured at or near the central portion of the stem, are arranged in the form of radii of a circle, and are all located in a plane perpendicular to the axis of the stem. The two outer holders of the first group and the two outer

holders of the second group are also in planes perpendicular to the axis of the stem.

The filament is wound in one continuous length over the different supports in such a manner that there is a support of the third group between any two points of support of the first and second groups. Commencing at holder b the filament passes for example to support c of group three, thence to support a of the first group, thence to support c^1 , thence to b^1 , to c^2 , and so on until the holder b^1 is finally reached. For attaching the filaments to the supports any of the well-known devices may be used; all of the supports may be provided with eyes as indicated on the drawing or hooks may be used instead.

By arranging the first and second groups in the form of radii of semi-circles the filament is spread out over the greatest possible area for the length of support used, the distance between adjacent portions of the filament is large and at the same time a much more uniform distribution of light in all directions is secured than is obtained by the usual methods of mounting filaments. The two holders to which the leads d, d^1 are attached are also as far apart as possible and danger of arcing between them is reduced to a minimum.

What I claim is:

1. In an electric incandescent lamp, the combination with a central stem, of a group of filament holders arranged in the form of radii of a semi-circle at the top of the central stem in the same plane as its axis, of a group of filament holders in the same plane also arranged in the form of radii of a semi-circle at the foot of the central stem, of a third group of holders arranged in the form of radii of a circle between the first two groups, and of a filament between the two outer holders of the second group which is wound on the frame in such a manner that there is always between one support of the first group of holders and another in the second group a support in the middle group.

2. In an electric incandescent lamp, the combination with a central stem, of a group of filament holders arranged in the form of radii of a semi-circle at the top of the central stem in the same plane as its axis, of a group of filament holders in the same plane also arranged in the form of radii of a semi-

circle at the foot of the central stem, of a third group of holders arranged in the form of radii of a circle between the first two groups in a plane perpendicular to the axis of the central stem, the two outer holders of the second group being in a plane perpendicular to the axis of the central stem and serving as connections for the current leads, and of a filament between the two outer holders of the second group which is

wound on the frame in such a manner that there is always between one support of the first group of holders and another in the second group a support in the middle group.

In testimony whereof I affix my signature in presence of two witnesses.

FRIEDRICH DICKENSCHIED.
